John Boston
WITNESS:

UNITED STATES PATENT OFFICE.

ELIZABETH G. ADRIAN, OF NEW YORK, N. Y.

DESIGN FOR A DOLL.

Application filed July 13, 1925. Serial No. 14,075. Term of patent 7 years.

To all whom it may concern:

Be it known that I, ELIZABETH G. ADRIAN, a citizen of the United States, residing at New York city, in the county of New York and State of New York, have invented a new, original, and ornamental Design for a Doll, of which the following is a specification, reference being had to the accompanying drawing, forming part thereof.

In the drawings:—

I claim:—

The ornamental design for a doll, as shown.

ELIZABETH G. ADRIAN.
